UNITED STATES PATENT OFFICE.

WILLIAM J. HALL, OF CHICAGO HEIGHTS, ILLINOIS, ASSIGNOR TO AMERICAN MANGANESE STEEL COMPANY, OF CHICAGO, ILLINOIS, A CORPORATION OF MAINE.

BUCKET FOR PLACER DREDGES.

Application filed September 9, 1922. Serial No. 587,052.

To all whom it may concern:

Be it known that I, WILLIAM J. HALL, a citizen of the United States, residing at Chicago Heights, in the county of Cook and 5 State of Illinois, have invented certain new and useful Improvements in Buckets for Placer Dredges, of which the following is a specification.

This invention relates to buckets used for 10 dredging and such like purposes, and which are required to be heat treated in order to properly condition the metal of which they are constructed.

The object of the invention is to provide a 15 construction of dredge bucket, the main body of which can be produced by casting, and can be successfully and completely heat treated to properly condition the metal of which it is formed. The invention finds 20 special application to dredge buckets of the kind which are operated in an endless chain, and particularly to those of large capacity and heavy massive construction.

In order that buckets of this type may 25 withstand the severe shocks and wear to which they are subjected in use, special alloy steel, such as manganese steel, is extensively used in their production. But the great variation in thickness of metal forming 30 different portions of these buckets gives rise to many foundry problems, particularly when manganese steel is employed in producing them. One of the characteristics of manganese steel is its high co-efficient of 35 expansion, amounting to as much as $\frac{1}{15}$ ths of an inch per foot between the temperature at which the metal is poured and the cold state, and this shrinkage has to be taken into consideration in order to avoid cracks and 40 internal stresses that would be detrimental to the casting.

Again, in the normal cast state, manganese steel is very brittle, being a compound of austenite (a solution of iron manganese and the carbide of iron and manganese) and free cementite (composed of the carbides of iron and manganese which remain undissolved). But since heating of the cast metal to proper temperature decomposes the cementite and renders the whole structure austenitic, which latter condition can be retained 45 by plunging the casting into cold water, and which condition produces a unique metal which is ductile, highly resistant to wear and

of great strength, the practice has grown up 55 of heat treating manganese steel castings. And here again the inequality in thickness of the various parts of a cast metal dredge bucket enters in to complicate the problem of production.

Cast manganese steel can ordinarily be 60 successfully heat treated up to sections of about four inches in thickness. Moreover, a light section properly heat treated is much stronger and of better shock resisting quality than a heavy section improperly treated.

But it is not always practicable to reduce 65 sections of manganese steel castings in certain directions sufficiently to bring them within the tempering range, owing to the 70 necessity of maintaining high orders of strength in such directions, and a serious problem is often presented in the design of proper sections. This is particularly true 75 with respect to the knuckles and eyes which constitute the hinging connections on dredge buckets where, in addition to opening up the metal to insure heat treatment, volume of 80 metal must be maintained in certain directions sufficient to insure very high load carrying capacity. In practice, a single bucket of this type may embody upwards of a ton 85 of metal in its structure, and may enter into an endless chain of such buckets, developing tensional strains upon their connecting 90 knuckles and eyes amounting to many tons, so that reduction in the section of such connections in the direction of loading is out of the question.

The present invention provides a construction of dredge bucket which can be successfully produced from manganese steel by casting and subsequent heat treatment, and the invention consists in the construction 95 hereinafter described, whereby ample resistance to shocks, stresses, and erosion imposed upon the bucket in use, is insured, and the portions of the structure which ordinarily present thicknesses in excess of those which can be successfully heat treated, are opened 100 up or interiorly exposed to heat conduction essential to uniform heating and cooling.

In the accompanying drawings—

Figures 1 and 2 are, respectively, a vertical central longitudinal section and a horizontal section of one form of dredge bucket 105 embodying the subject-matter of the inven-

tion; the section of Figure 2 being in a plane indicated by the line 2^x—2^x of Figure 1.

Figure 3 is a front elevation of one of the two symmetrically formed sides of the bucket.

Figures 4, 5, and 6 are detailed sections taken, respectively, in planes indicated by the lines 4^x—4^x, 5^x—5^x and 6^x—6^x of Figure 1.

10 Figures 7 and 8 are, respectively, a side elevation and a horizontal section of another design of bucket in which the features of the invention are embodied; the section of Figure 8 being in a plane indicated by the line 8^x—8^x of Figure 7.

Figure 9 is a front elevation of one of the two symmetrically formed sides of the bucket shown in Figures 7 and 8.

20 Figures 10, 11, 12, and 13 are detail sectional views of parts of the bucket shown in Figures 7 and 8; the planes of the several sections being indicated in Figure 7 by the lines 10^x—10^x, 11^x—11^x, 12^x—12^x, and 25 13^x—13^x, respectively.

25 As shown in both of the embodiments selected for the purpose of illustrating the invention, a dredge bucket, of the kind employed in an endless chain, comprises a bowl 1 having a scraping lip 2, an inclined bottom 3, an approximately cylindrical hinging knuckle 4 (Figs. 1 and 2) or 4^a (Figs. 7 and 8) transversely disposed across its rear end, and hinging eyes 5 (Figs. 1 and 2) or 5^a (Figures 7 and 8) spaced 30 apart at its front end in position to receive between them the hinging knuckle 4 or 4^a to which they are pivotally connected by pintles passing through bores 6, 7, (Figs. 1 and 2) or 6^a, 7^a (Figs. 7 and 8). It is 35 also customary to provide dredge buckets of this kind with bottom shoes 8 (Figs. 1 and 2) or 8^a (Figs. 7 and 8) upon which they are supported in traversing their bridge or track, and passing around the 40 sprockets or tumblers at the end thereof. But these knuckles, eyes, and shoes, in order to develop resistance to destructive forces 45 encountered in use, require to be made with dimensions in excess of that which can be 50 successfully heat treated in manganese steel.

55 The present invention admits of the use of dimensions for the before-mentioned parts in the directions in which the destructive forces are imposed upon them in use, but opens up these parts in a manner to afford access of heat to and from the interior thereof in heat treating and quenching or cooling.

60 According to Figures 1 and 2, the knuckle 4 is provided with a series of external channels 9 running in planes parallel to the direction of draft transmitted through the hinging connection, and leaving, in positions alternating with said channels, an-

nular strengthening sectors 10. According to Figures 7 and 8, the channels 9^a are of more uniform depth throughout the semi-circumference of the approximately cylindrical hinging knuckle, thereby leaving annular strengthening sectors 10^a of greater mass than the sectors 10 of Figures 1 and 2, which increased dimension will be desirable where the bucket is constructed with great capacity. By means of the channels 9 or 9^a, considerable areas of the wall of the pintle bore are reduced to a transverse dimension which permits absorption and giving off of the heat entirely through the metal section, while the depth of the channels is such as to expose lateral faces 10^x or 10^{ax} upon the strengthening sectors 10 and 10^a, thereby avoiding exclusion of heat from parts radially within said sectors. In this way, a massive, substantially durable, and properly heat-treated hinging knuckle is developed on the bucket.

85 In order to insure proper heat-treatment of the shoes 8 or 8^a, channels 11 or 11^a are formed therein which serve similarly to reduce the thickness of these shoes through a sufficient area thereof to insure heat absorption and delivery throughout the entire mass of the metal. The channels 11 or 11^a may, if desired, be continuations of 90 the channels 9 or 9^a; or said channels in the shoes or bottom may extend in any other desired direction with similar results.

95 An important advantage in using the channels in the bottoms or shoes is that they 100 resist the peening action or flow of metal on the bottom of the bucket, due to pounding which the bucket receives in passing over rollers upon its bridge or around the sprockets or tumblers at the ends of the 105 bridge.

110 In order to form the hinging eyes 5 or 5^a in a manner to render them subject to thorough heat treatment without detracting from the strength which they are required 115 to possess in use, these eyes are recessed or opened up in one or another of several ways, two of which are herein shown by way of illustration.

120 According to the construction shown in Figures 1, 2, 3, and 6, the eyes 5 are provided with slots 12 extending through the vertical and longitudinal dimensions of 125 said eyes, except for an annular sector 13 left at the front of the eye in position to render continuous the draft bearing of the hinging pintle throughout the transverse dimension of the eye; lugs 14, projecting into the slot from one of the two walls 15 thus formed, being preferably provided in a manner to insure additional heat absorption and distribution, and to position a separate filling piece inserted to complete the pintle bearing when in use. Moreover, the outer wall 16 left by the slot 12 is pro- 130

vided with a rearwardly extending slot 17 which further opens up this portion of the metal. The result of this construction is a complete cylindrical wall defining the pintle bearing 6 to the extent of the thickness of the wall 15, and a bearing for said pintle limited to the front sector 13 in the outer wall 16 of the eye.

According to Figures 7 and 8, the eye 5^a is provided with an exterior approximately semi-annular groove 18 which leaves intact a semi-cylindrical front bearing for the pintle, and the entire lug of the eye member in rear of said semi-cylindrical bearing is slotted through from side to side, as shown at 19. Here, the elongated lugs 20 are provided (see also Figures 12 and 13) for the purpose of distributing heat to and from the adjacent parts, and positioning a filler block or other inserted piece, employed for completing the bearing.

To further open up the slide shoes, and particularly in view of their relation to the inclined bottom 3, to which they extend in an angular direction, these slide shoes may be provided with lateral recesses 21, 21^a, 22, 22^a, between them and the bottom 3, which leave the slide shoes of reduced section.

I claim:

1. A cast metal dredge bucket formed at bottom with slide shoes and having channels intersecting said slide shoes, reducing the thickness of the metal thereof, and opening up said metal to the absorption and giving off of heat in heat treatment of the casting.

2. A cast metal dredge bucket constructed with an integral hinge knuckle near its bottom, and with slide shoes upon its bottom adjacent to said knuckle; said knuckle being provided with a transverse bore to receive a pintle and having in the wall of said bore external channels leaving strengthening ribs alternating with reduced wall sectors; and said channels extending along the slide shoes.

3. A cast metal dredge bucket having upon its bottom slide shoes integral therewith, said slide shoes being provided with channels developing areas of reduced thickness alternating with surface ribs and exposing the sides of said ribs and metal lying inwardly from the channels to the absorption and giving off of heat in the heat treatment of the casting.

4. A cast metal dredge bucket having an inclined bottom and slide shoes integral with said bottom and extending at an angle thereto; said slide shoes having recesses extending laterally thereinto between portions of their treads and the inclined bottom to open up

the metal of the casting for the absorption and giving off of heat in heat treatment.

5. A cast metal dredge bucket having an integral hinging eye provided with a bore to receive a pintle, and having a slot extending inwardly from the pintle bore to open up the metal of the eye for the absorption and giving off of heat in heat treatment of the casting.

6. A cast metal dredge bucket having an integral hinging eye provided with a bore to receive a pintle, and having a slot extending inwardly from the pintle bore to open up the metal of the eye for the absorption and giving off of heat in heat treatment of the casting; said slot lying in a vertical plane.

7. A cast metal dredge bucket having an integral hinging eye provided with a bore to receive a pintle, and having a slot extending inwardly from the pintle bore to open up the metal of the eye for the absorption and giving off of heat in heat treatment of the casting; said slot lying in a vertical plane and extending through the eye to its forward end.

8. A cast metal dredge bucket having an integral hinging eye provided with a bore to receive a pintle, and having a slot extending inwardly from the pintle bore to open up the metal of the eye for the absorption and giving off of heat in heat treatment of the casting; said slot lying in a horizontal plane; and said eye being also provided with an external channel surrounding the front wall of its pintle bore.

9. A cast metal dredge bucket having an integral hinging eye provided with a bore to receive a pintle, and having a slot extending inwardly from the pintle bore to open up the metal of the eye for the absorption and giving off of heat in heat treatment of the casting; said slot lying in a horizontal plane; said eye being also provided with an external channel surrounding the front wall of its pintle bore; and said channel extending inwardly and merging with said slot.

10. A cast metal dredge bucket having an integral hinging eye provided with a bore to receive a pintle, and having a slot extending inwardly from the pintle bore to open up the metal of the eye for the absorption and giving off of heat in heat treatment of the casting; said slot lying in a vertical plane; and the walls of said slot being provided with lugs extending into the slot and adapted to support a filling block.

Signed at Chicago Heights, Illinois, this 30th day of August, 1922.

WILLIAM J. HALL.
